POSTING TRAY

Adolph G. Lotter, Milwaukee, Wis., assignor to
 Stationers Loose Leaf Company, Milwaukee,
 Wis., a corporation of Wisconsin

Application December 16, 1944, Serial No. 568,439

8 Claims. (Cl. 129—16)

1

This invention relates to posting trays of the type used in connection with bookkeeping machines to hold for ready accessibility a stack of loose record sheets upon which various data is kept.

In posting trays of this type the record sheets are generally held in an upright or slightly rearwardly inclined position clamped between a longitudinally adjustable backrest adapted to be releasably secured in any of a number of longitudinal positions of adjustment and a front pressure plate capable of being withdrawn from the front of the stack of sheets to provide access thereto for the entrance of data and other information thereon.

It is an object of the present invention to provide a posting tray of this general type with a front pressure plate mounted in a novel manner within the tray so as to improve the accessibility of the record sheets upon withdrawal of the pressure plate to an inoperative position.

More particularly it is an object of this invention to provide a front pressure plate for posting trays of the character described with a novel clamping and withdrawing action enabling the plate to be advanced from a forwardly tilted inactive position to a rearwardly tilted clamping position cooperating with a backrest to clamp a body of sheets therebetween in an upright rearwardly inclined position.

A further object of this invention is to connect the front pressure plate to a posting tray of the character described by a novel locking hinge to enable the plate to be actuated to and from a locked clamping position with respect to a bank of record sheets.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate one complete example of the physical embodiment of the invention constructed in accordance with the best mode so far devised for the practical application of the principles thereof, and in which:

Figure 1 is a perspective view of a posting tray equipped with the novel front pressure plate of this invention and shown with the same in operative clamping position;

2

Figure 2 is a view similar to Figure 1 but illustrating the pressure plate in its retracted position and with one side of the tray swung open so as to provide maximum accessibility to the stack of record sheets;

Figure 3 is a perspective view of a portion of the interior of the tray looking toward the front end thereof;

Figures 4 and 5 are longitudinal cross sectional views illustrating the manner in which the pressure plate is actuated to its operative clamping position; and

Figure 6 is a fragmentary perspective view of the interior of the tray showing the latch mechanism by which the hinged side wall of the tray is releasably held in an upright position closing one side of the tray.

Referring now more particularly to the accompanying drawings in which like numerals indicate like parts, the numeral 10 designates generally the tray of this invention which comprises front and back walls 11 and 12 respectively, opposite side walls 13 and 14 and a bottom wall 15. The tray is preferably provided with laterally spaced longitudinal raised bottom sections 16 providing a false bottom for the tray, the top surfaces of which are fluted for the purpose of minimizing slippage of record sheets normally held in a rearwardly inclined stack 17 between a backrest 18 and a front pressure plate 19.

The backrest 18 is preferably of the automatically locking type in that it may be moved longitudinally forwardly toward the front of the tray at will but in that it requires releasing from clamping position on a guide rod 20 for motion toward the back of the tray.

This type of backrest is well known in the art and hence further description thereof is deemed unnecessary, it being sufficient to note that the backrest is guided for such longitudinal motion by means of a channel member 21 secured to the bottom of the tray with its back flatwise engaged therewith and having flanges 22 at its sides to hold the false bottoms 16 separated. The upright flanges 22 have inwardly directed rails 23 bent therefrom to overlie the back of the channel in spaced relation thereto and which cooperate therewith in the formation of tracks in which rollers 24 on the backrest are received.

The channel member 21 may extend the full length of the tray to terminate adjacent to the front wall 11, and if desired, may act to guide the front pressure plate 19 for motion between its retracted and clamping positions.

In the present instance, however, a separate guideway is provided for this purpose similar to the guideway 21 and consists of a relatively short channel shaped member 25 mounted with its back flatwise against the channel 21 and having upright flanges 26 at its side edges spaced inwardly from the flanges 22 of the outer channel member. The flanges 26 are also provided with rails 27 bent inwardly therefrom to overlie the back of the channel and cooperate therewith in the formation of tracks for the reception of rollers 28 carried by the front pressure plate 19 at its bottom portion.

Inasmuch as the bottom edge of the front pressure plate terminates just above the false bottoms 16 it is necessary to provide a central downward extension 29 having bifurcations 30 disposed to either side of the guide rod 28 and provided with forwardly directed ears 31 upon which the rollers 28 are pivotally mounted. The tracks for the rollers 28 thus provide for sliding motion of the pressure plate longitudinally of the tray and pivotal motion about the axis of the rollers 28.

Longitudinally spaced stops 32 and 33 adjacent to the front wall 11 and the rearward end of the channel 25 limit such sliding motion of the pressure plate within the guide upon engagement of the bifurcated ends of the extension 29 therewith.

The pressure plate 19 is also connected to the tray by means of a hinge 35 having flaps 36 and 37 hingedly connected together as at 38 on a main hinge axis and having their ends hingedly connected as at 39 and 40 to the front wall of the tray and the back of the pressure plate respectively at substantially opposite points and substantially at the elevation of the top edge of the tray.

It is important to note that the hinge connections at the ends of the flaps are located slightly below the horizontal median plane of the pressure plate 19. This disposition of the hinges, in effect, renders the pressure plate 19 top heavy so that upon being withdrawn from its operative clamping position shown in Figure 1 the plate will remain in an overbalanced rearwardly inclined position until engagement of the bifurcations 30 with the stop 32 effects pivotal movement of the plate about the axis of the rollers 28 to a position at which the plate overbalances in a forward direction to lean in a forwardly inclined position against the front wall 11 of the tray.

Due to the combined action of the hinge 35, the tracks on the channel 25, and the top heavy condition of the plate the same will remain in this forwardly inclined position resting against the top edge 41 of the front wall 11 of the tray when moved to its retracted position as shown in Figure 2.

A handle 42 carried by the hinge flap 36 and adapted to be grasped between the thumb and second finger of the hand of an operator provides for shifting the hinge flaps and hence actuating the plate 19 between its operative and retracted positions. This handle extends across the main hinge axis 38 to overlie the flap 37 which engages therewith in the operative clamping position of the plate 19 to limit hinge motion of the flaps at a point such that the main hinge axis 38 is disposed slightly below the plane joining the hinge axes 39 and 40. The hinge 35 thus acts as a toggle to releasably lock the plate 19 in position against the front of the

stack of record sheets and clamped against the backrest 18.

In withdrawing the plate 19 to inoperative position by pulling on the handle 42 to swing the main hinge axis 38 upwardly and outwardly over the edge 41 of the tray toward a position at which the flaps 36 and 37 are folded upon each other, the top edge of the pressure plate 19 remains in engagement with the first sheet of the stack, as shown in dotted lines in Figure 2, up until the time the bottom of the pressure plate is being pulled away from the stack of sheets abuts against the stop 32 to initiate pivotal motion of the plate about its rollers 28. This prevents the first sheets of the stack from following the withdrawn plate.

It frequently occurs that during posting a number of record sheets at the front of the stack slump down to positions as indicated at 43 in Figure 4 due to frequent transfer of sheets from their rearwardly inclined positions resting against the backrest 18 to forwardly inclined positions resting against the retracted pressure plate. Unless manually restacked in their proper positions, these slumped down sheets 43 prevent proper closure of the pressure plate 19 and often times are damaged by the clamping operation.

In the present instance, however, these sheets 43 are automatically restacked by advancement of the plate to its operative clamping position. As clearly shown in Figures 4 and 5, the plate 19 has a hook 44 formed on its back which occupies a position directly adjacent to the handle 42 in the retracted position of the plate. This hook is adapted to be engaged by the index finger of the operator as shown during actuation of the plate to its clamping position to prevent premature pivotal movement of the pressure plate 19 about the axes of its rollers upon engagement of the bottom edge of the plate with the displaced record sheets 43.

Hence, these sheets 43 are forced backwardly and upwardly by the rearwardly advancing plate until they are realigned with the upright sheets of the stack. The hook 44 is released as soon as the bottom edge of the plate 19 abuts the solid stack of sheets, and further application of pressure on the hinge 35 to bring its flaps to their outstretched locking position then effects the necessary pivotal motion of the plate to bring the same to its rearwardly inclined clamping position against the face of the stack of sheets.

The manner of actuating the pressure plate described distinguishes from past constructions wherein the plate is merely provided with pivotal motion at a point adjacent to the bottom of the stack of record sheets at the front face thereof. In the present case, it is to be noted that the entire pressure plate is slidable bodily between the stop 32 and the front of the stack of sheets and that forward and rearward pivotal motion of the pressure plate is effected upon engagement of the lower portion of the plate with the stop 32 and the stack of sheets respectively. Because of the bodily sliding motion of the pressure plate necessary to carry the same from its operative clamping position to an inoperative forwardly tilted position, maximum access is gained to the stack of sheets to facilitate work on any of the sheets.

Further accessibility may be provided if desired by having the side wall 14 mounted on a hinge 45 to swing outwardly as shown in Figure 2. The hinge 45 is disposed along the bottom of the wall and a latch mechanism 46 cooperat-

ing with a suitable keeper 47 on the tray holds the wall 14 in an upright position closing the side of the tray.

A pair of stops, only one of which is shown as at 48, carried by the side wall 14 engage stationary portions of the tray to limit outward swinging of the side wall so as to position a longitudinal abutment 49 in proper relationship with the stack of sheets so that their withdrawal from the stack 22 is limited thereby.

From the foregoing description taken in connection with the accompanying drawings, it will be readily apparent that the novel manner of mounting the front pressure plate of the posting tray of this invention facilitates its operation and provides ample accessibility to the stack of record sheets; and that misaligned record sheets are automatically aligned vertically with respect to the stack by advance of the plate to the clamping position.

What I claim as my invention is:

1. In a posting tray of the type having longitudinally spaced front and back walls joined by a bottom wall and having a rearwardly inclined backrest adjustable longitudinally between said front and back walls to support a stack of loose sheets in the tray in a rearwardly inclined position: a front pressure plate cooperating with the backrest to clamp said stack of sheets therebetween in said rearwardly inclined position; cooperating means on said plate and the tray mounting the plate for sliding motion longitudinally of the tray in the front portion thereof and for pivotal motion about a transverse axis; a hinge having one of its flaps hingedly connected to the front portion of the tray near the open top thereof and having the other of its flaps hingedly connected to the pressure plate at a point thereon substantially opposite said connection to the tray, said hinge being adapted to swing from a position with its flaps outstretched to a position in which the flaps are substantially folded upon each other with the main hinge axis above said hinge connections to shift the pressure plate from an operative position spaced a distance from the front wall of the tray clamping a stack of sheets between it and the backrest to an inoperative withdrawn position adjacent to the front wall of the tray providing access to the stack of sheets; and a stop on the tray engaged by a portion of the plate below the hinge connection thereto during withdrawal of the plate from its clamping position to effect pivotal motion of the plate about its pivotal connection to the tray whereby the plate pivots from a rearwardly inclined operative position to a forwardly inclined retracted position spaced from the stack of sheets during actuation of the hinge to bring its flaps into substantially folded relationship.

2. In a posting tray having longitudinally spaced front and back walls joined by a bottom wall and having a rearwardly inclined backrest carried by longitudinal guide means on said bottom wall and adapted to be adjustably secured in any of a number of positions longitudinally of the tray: a front pressure plate movable from an operative rearwardly inclined position cooperating with the backrest to clamp a stack of loose sheets therebetween to a retracted forwardly tilted position spaced forwardly of the stack of sheets to provide access thereto; cooperating means on the plate and the tray mounting the same for sliding movement between its operative and retracted positions and for pivotal motion

of the plate about transverse axes adjacent to the bottom of the tray; and means by which the plate may be actuated to its operative and retracted positions comprising a hinge, the flaps of which are separately hingedly connected to the plate and the tray at substantially opposite horizontal points thereon, said hinge being adapted to swing from a position with its flaps outstretched and its main hinge axis spaced slightly below said hinge connections in the operative clamping position of the plate to a position with its flaps substantially folded upon each other and the main hinge axis spaced above said hinge connections in the retracted position of the plate; a stop on the tray engaged by a bottom portion of the plate during sliding motion thereof to its retracted position to cause the plate to swing from its rearwardly inclined position to a forwardly inclined position; and means on the hinge for defining the outstretched position of the flaps and for locating the main hinge axis slightly beneath the plane defined by said hinge connections upon actuation of the hinge to place the pressure plate in its operative clamping position.

3. The posting device of claim 2 wherein said last named means provides a handle for actuating the hinge and consequently for controlling the movements of the pressure plate between its operative and retracted positions.

4. The posting device defined by claim 2 wherein said hinge connections lie beneath the horizontal median plane of the pressure plate so that the plate is rendered top heavy and remains in a rearwardly inclined position during retraction prior to engagement thereof with said stop, and so that the plate remains in a forwardly inclined retracted position after pivotal motion thereof upon engagement with said stop.

5. The posting device defined by claim 2 characterized by the provision of handle means on the hinge for actuating the same and consequently for controlling the movements of the pressure plate between its operative and retracted positions, and further characterized by the provision of other handle means on the pressure plate disposed adjacent to the handle means on the hinge in the retracted position of the plate adapted to be grasped simultaneously therewith by an operator during actuation of the hinge to advance the plate to its operative position to preclude premature rearward tilting of the plate about its pivotal connection with the tray in the event of interference with sliding thereof toward the stack of leaves to thereby insure proper positioning of slumped down sheets at the front of the stack during the clamping operation.

6. In a posting device having a bottom wall and upright side and end walls defining an open topped tray, one of said end walls forming the front of the tray: means on the bottom wall of the tray forming a longitudinal guideway leading rearwardly from the front of the tray; a front pressure plate for said tray; means connecting the plate with the guideway for sliding motion longitudinally of the tray along said guideway and for flatwise pivotal motion of the plate toward and from the front of the tray; a hinge having its flaps separately connected to the pressure plate and the front wall of the tray at points substantially on a level with the top edge of the front wall of the tray, said hinge being adapted to be swung from a substantially folded position with the hinge connections adjacent to one another and the main hinge axis spaced

thereabove to a position at which its flaps are outstretched with the main hinge axis disposed slightly beneath said hinge connections to move the plate between retracted and operative positions respectively; and a stop adjacent to the forward end of said guideway for limiting sliding motion of the plate therein during folding of the hinge to retract the pressure plate to thereby cause the pressure plate to pivot during final closing of the hinge to a forwardly inclined position resting against the front wall of the tray; and said pressure plate being so balanced about its hinge connection with the hinge flap adjacent thereto that the plate advances rearwardly away from said front wall of the tray while in said forwardly inclined position upon actuation of the hinge to bring its flaps to said outstretched condition until engagement of the bottom leading edge portion of the plate with a stack of sheets supported in the tray in a rearwardly inclined position limits said advance and initiates rearward tilting of the pressure plate during final motion of the flaps to their outstretched position.

7. The posting device defined by claim 6 wherein said pivotal and sliding connection between the pressure plate and the guideway at the bottom of the tray comprises laterally spaced longitudinal tracks on the tray and rollers carried by the pressure plate and engaged in said tracks so as to permit sliding of the plate in the tray and pivotal motion of the plate at any point between said stop and the stack of sheets.

8. In a posting tray of the character described having a bottom wall and a front wall: a guideway on the bottom wall of the tray leading rearwardly from the front wall of the tray, said guideway including laterally spaced upright

flanges having portions directed inwardly toward each other spaced from and overlying the bottom of the tray to form longitudinal tracks; a front pressure plate having rollers on its bottom portion engaged in said tracks constraining the plate to sliding motion toward and from said front wall and pivotal motion on axes parallel to the front wall of the tray; stop means carried by the tray for limiting sliding motion of the pressure plate in said guideway; and a hinge having flaps hingedly connected to one another and independently connected to the pressure plate and the tray at substantially horizontally opposite points with the main hinge axis defined by the hinge connection between the flaps adapted to be swung arcuately between elevated and depressed positions spaced above said hinge connections and slightly below the plane passing through the axes of said hinge connections respectively to carry the pressure plate from an inoperative retracted forwardly tilted position to an operative position defined by the front of a stack of sheets to be clamped entailing both sliding of the plate in said guideway and pivotal motion thereof on its rollers.

ADOLPH G. LOTTER.
